US00D903214S

(12) **United States Design Patent** (10) Patent No.: **US D903,214 S**
 Williams et al. (45) Date of Patent: **** Nov. 24, 2020**

(54) **ROBOT AND SERVICE MODULE**

- (71) Applicant: **Discovery Robotics**, Pittsburgh, PA (US)
- (72) Inventors: **Larry J. Williams**, Pittsburgh, PA (US); **Vivek Rajendran**, Pittsburgh, PA (US); **Naman Kumar**, Pittsburgh, PA (US); **Hardik Shah**, Pittsburgh, PA (US)
- (73) Assignee: **Discovery Robotics**, Pittsburgh, PA (US)
- (**) Term: **15 Years**
- (21) Appl. No.: **29/660,924**
- (22) Filed: **Aug. 23, 2018**
